UNITED STATES PATENT OFFICE.

WILHELM SADTLER, OF HOMBURG-ON-THE-HÖHE, GERMANY, ASSIGNOR TO THE FIRM
OF ERNST PAUL LEHMANN, OF BRANDENBURG-ON-THE-HAVEL, GERMANY.

TOY.

1,094,749.

Specification of Letters Patent. Patented Apr. 28, 1914.

Application filed January 25, 1913. Serial No. 744,200.

To all whom it may concern:

Be it known that I, WILHELM SADTLER, a subject of the King of Prussia, residing at No. 28 Brendelstrasse, Homburg-on-the-Höhe, Germany, have invented new and useful Improvements in Toys, of which the following is a specification.

My invention relates to improvements in toys, particularly of that class, for which I have obtained Letters Patent in the United States dated October 15th, 1912, and numbered 1,041,677.

The principal feature of this class of spring- or motor-driven toy consists in deflecting their line of motion, as they run along the edge of a table or other supporting surface, said change of the direction of motion being obtained by an arm or feeler extending forwardly from the toy and controlling steering means connected with the toy.

The improvements of the present invention have for their purpose, partly to substitute means of greater simplicity for the arm or feeler running in advance of the toy proper, and partly to provide means for changing the path of motion of the toy independently of the said controlling arm or feeler or the means provided to replace the same. The toy, thereby, will be enabled to perform a greater variety of changes in traveling on its supporting surface or table. According to my prior invention mentioned above, the toy would move along the edge of a table or supporting surface and, at the corner of said table or surface, would turn to follow the adjacent edge, and thus the toy could move around about the table always following its edges. According to the present invention, the toy may be made to periodically turn away from the edge of the table, run across the surface of the table to its opposite edge, then follow said opposite edge for a certain time and turn away again from the same to cross to another edge, and so on.

To make my invention perfectly understood, I have illustrated the same in the accompanying drawings, in which—

Figure 1 is a side-elevation of a toy car embodying various features of this invention, and Fig. 2 is an underside plan view of the construction shown in Fig. 1. Fig.

3 is a side elevation showing a modified construction according to this invention. Fig. 55 4 is a side-view of a steering wheel constructed according to another modification of this invention. Fig. 5 is a plan view of a portion of a toy provided with a steering wheel according to Fig. 4. Fig. 6 is a side-elevation of a toy-car provided with steering means according to another modification of this invention. Fig. 7 is a similar side-elevation of the same construction shown in Fig. 6, with the parts occupying another 65 position, and Fig. 8 is a side-elevation of a toy-car illustrating another modification of the same invention.

Referring, first, to Figs. 1, and 2, the traveling toy, having, as an example, the 70 shape of a toy-car, 1, has one of its fore-wheels 2, formed or provided with a projecting flange 3, similar to that of a railway-wheel, the other fore-wheel of the car being a common car-wheel of any kind. The 75 said flange 3, running along the side of the edge 4 of the table or supporting surface, has the same function as the steering arm or feeler described and shown in my previous Patent No. 1,041,677, and, accordingly, is 80 well adapted to replace said feeler. Supposing the car 1, to be provided with a wheel of this kind and having, as described and shown in my previous patent aforesaid, a steering wheel 13 carried by a shaft or rod 85 14, a lateral pin 14', to which one end of a spring 15 is secured extending from said rod 14, the other end of said spring being attached to the car-frame 1, the said flange 3 of wheel 2, while closely following the 90 side of edge 4 of the supporting table, will prevent the said steering-wheel 13 from being turned by the spring 15, and the car will closely follow the straight line of said edge 4. When the said wheel 2 reaches a 95 corner of the table, the projecting flange 3 of said wheel will be able to turn around said corner and as it offers no further resistance to the traction of the spring 15 tending to turn the rod 14 and steering 100 wheel 13, the said steering wheel will at once be caused to take an oblique position, which causes the car to change its course and to turn around the corner of the table which had been reached by said wheel 2. 105 The car being steered by the steering wheel

13 from the left to the right side of its path of motion (Fig. 2), causes the said wheel 2, and along with it the other wheel at the opposite end of its axle, to take the corresponding oblique position, thereby causing the wheel 2 to turn around the corner and the opposite wheel to follow the same direction. It will be seen, that by such simple means the feeler or arm running in advance of the car might be replaced. The natural appearance of the motor-car would not further be impaired by the feeler extending in advance of the car, as in the former construction. Such natural appearance, moreover, can be fully maintained by placing a common running wheel at the other end of the axle of wheel 2, as shown in Fig. 2.

On providing a common second wheel, 20 as described, it will be preferable to pivotally support the said axle, by providing trunnions, as at 5, turning in bearings of the frame. At or near the sides of the frame 1, the said axle is guided in vertically elongated bearings of a known kind provided in the frame-sides which offer a sufficient play in the vertical direction thereby allowing the axle of wheel 2 to be raised or lowered. The trunnions 5, should, preferably, be located nearer to the common wheel than to the flanged wheel 2. By this means, when the flanged wheel 2 turns around a corner and temporarily loses its supporting surface, the other or common 35 wheel will be slightly lifted by the greater weight of the flanged wheel, and by such lifting the common wheel will be prevented from jarring against the supporting surface and thereby from offering resistance 40 against the turning of the car.

The flanged wheel 2, instead of carrying a concentrical flange, might be formed in the shape of a lateral scroll, as illustrated by Figs. 4, and 5. The innermost volute of 45 said scroll is cylindrical and will, first, be placed on the edge 4 of the table. As the car proceeds, the increasing diameter of the volutes will raise the wheel till the outermost or largest volute comes to level of 50 the supporting surface or table, and from that moment the scroll acts no more as a flange to prevent the steering-wheel 13 from being turned by the spring 15, but the wheel 2 will be steered by the steering-wheel 13, 55 which, having been forced into an oblique position, will cause the car to be directed away from the edge 4 of the table and toward the opposite edge.

It will be seen that, with this construction 60 of the flanged wheel the toy will be steered away from the edge of the supporting table not only when a corner has been reached, but at any portion of the length of the edge, when the scroll, which acts as a flanged wheel, has performed as many revolutions

to bring the outer periphery of the scroll-wheel to the level of the table and thereby remove the resistance, which, before, the said scroll wheel had offered to the turning of the steering wheel. The period between any two succeeding steering actions will depend on the time within which the scroll-wheel is being raised by its own revolutions to the level of the table. By increasing or diminishing the volutes of the scroll, or by accelerating or retarding the speed of revolution of said scroll-wheel, the periods within which the toy automatically changes its course may be determined.

Other equivalent means for obtaining a change of the course of the toy by lifting the flanged wheel out of contact with the resisting edge of the table at any intermediate portion of the length of said edge, may be substituted. According to one modification, such means consist of providing means for forcing the steering wheel 13 down against the surface of the table and thereby raise the forward portion of the car with the flanged wheel 2 so much to lift the flange 3 beyond the edge of the table. The corresponding construction is incorporated in Figs. 1 and 2 of the drawings. The steering-wheel 13, normally is kept clear or only slightly touching the surface of the supporting table. The rod 14 of said steering-wheel has two collars and between said collars the rod 14 is engaged by the fork of a lever 18 the pivot-point of which is at 17. A driving wheel mounted on the spring-barrel 6 carries a pin 19, which, as the said spring-barrel revolves, strikes said lever 18 from below, thereby forcing the forked arm of said lever down and forcibly pressing the steering wheel 13 against the supporting surface. The upper collar carried by the rod 14, accordingly, will lift the forward portion of the car 1 and raise the flanged wheel 2 so much to make the flange 3 rise beyond the level of the edge 4. When the pin 19 has passed below the lever 18, the pressure which had forced the wheel 13 against the surface of the table, will be released and the said steering wheel 13 will be able to steer the car under the tension of its spring 15. The car will, then, move to the opposite edge of the table and on reaching said edge, the flanged wheel will descend with its flange below said edge. The car, then, will proceed along said edge till the pin 19 again will lift the lever 18 and force down the wheel 13, thereby raising the wheel 2 and causing the car again to change the direction of its course across the table, as before described.

If, instead of using a flanged wheel 2, a feeler rigidly secured to the toy is employed, as fully described in my previous Patent No. 1,041,677, the effect will be the same; the said rigid feeler, being raised be-

yond the level of the edge 4 of the table, will leave the car to be steered by its steering-wheel 13. A modification of this construction is shown in Fig. 3. The steering-wheel 13 is carried by a rod 14 adapted to 5 turn under the tension of a spring 15. A feeler 20, sliding along the edge 4 of the supporting table, normally prevents said steering-wheel from being turned. The said feeler is pivotally secured to the car as at 10 21. The rear end of said feeler 20 is provided with a slot 22 within which works an eccentric pin 24 carried by any one of the revolving wheels 23 of the driving gear. It 15 will be easily seen, that, when said pin 24 reaches the lower end of its circular path, the slotted portion of the feeler will be depressed and the forward portion, accordingly, raised above the level of the table, 20 thus setting the steering-wheel 13 free to be swung by its controlling spring 15. Such steering will be repeated at intervals depending on the period of revolution of the wheel 23.

25 A further modification of this invention is illustrated by Figs. 6 and 7. It consists in providing two steering-wheels 26, and 27, independent of each other. The steering-wheel 26, is connected to the feeler 20 and acts substantially in the manner already described in my prior Patent No. 1,041,677 to 30 keep the toy running in a straight line along the edge of a table or supporting surface and to cause its automatically turning at 35 the corner of the table. The second steering-wheel 27 is carried by a rod 14 susceptible of being turned by a spring connected to it, the same as the steering-wheel 26. The said rod 14 carries two collars and a 40 forked lever 18 engages said rod 14 between the said collars, substantially as described with reference to Figs. 1 and 2. One of the 45 gear-wheels carries a pin 19, which lifts in each revolution the lever 18 and forces the rod 14 and steering-wheel 27 down from the position in Fig. 6 into the position indicated in Fig. 7. Owing to said downward pressure the forward portion of the toy-car is 50 lifted so much to raise the steering-wheel 26 and its feeler 20 from the position of Fig. 6 into the position of Fig. 7. The toy, then, is steered alone by the wheel 27 across the table.

Fig. 8 shows still another modification of 55 my invention, which differs from that illustrated in Fig. 1 by the fact, that the lever 18, on being struck by the pin 19, not only forces down the rod 14 of a steering-wheel, but simultaneously engages one arm of a 60 double-armed lever 28, fulcrumed as at 30, the other arm of which lever engaging the axle 29 of the flanged wheel 2, to lift the same in a vertical direction in its elongated 65 bearings, to set the same free of the edge of the table and permit the toy-car to travel

across the table to its opposite edge, substantially as described with reference to Figs. 1, and 2.

Driving power may preferably be supplied by a spring-actuated barrel 6 and a 70 train of wheels transmitting motion to one of the hind-wheels, say to the wheel 8. I prefer to mount one of the hind-wheels, say the wheel 11, on a trunnion 12 independent of the axle of wheel 8, to prevent said wheel 11, from being turned by friction of the axle of wheel 8. And I also prefer to locate said hind-wheel 11 slightly in the rear of the driven hind-wheel 8, to facilitate the steering 75 of the toy.

The toothed wheel 9 carried by the axle of the hind-wheel 8 serves to engage an escapement 31 carried by an idle axle 32 on which a weighted lever 33 is mounted. The said escapement and weighted lever serve to retard motion in a well-known manner. The said idle axle 32 has no connection with the other hind-wheel 11.

I claim as my invention:

1. In a toy, the combination with steering mechanism carried by said toy, of means for controlling the position of said steering mechanism in accordance with guiding surfaces encountered by said controlling means, and with means for automatically and temporarily making said controlling means inoperative, substantially as and for the purpose set forth.

2. In a toy, the combination, with steering-mechanism carried by said toy, of means for controlling the position of said steering mechanism in accordance with guiding surfaces encountered by said controlling means, and with means for automatically and temporarily raising said controlling means out of engagement with their guiding surfaces, substantially as and for the purpose set forth.

3. In a toy, the combination, with steering means carried by said toy, of means for controlling the position of said steering means in accordance with guiding surfaces encountered by said controlling means, said controlling means consisting of a fore-wheel carrying a projecting flange adapted to bear against the edge of the toy-supporting surface, substantially as set forth.

4. In a toy, the combination, with steering mechanism carried by said toy, of means for controlling the position of said steering means in accordance with guiding surfaces encountered by said controlling means, said controlling means comprising a fore-wheel having peripheral supporting surfaces at different distances from its axis, substantially as and for the purpose set forth.

5. In a toy, the combination, with a steering wheel carried by said toy, of means for controlling the position of said steering wheel in accordance with guide-surfaces en-

countered by said controlling means, and with means for automatically and temporarily forcing the said steering wheel down against its supporting surface, substantially as and for the purpose set forth.

6. In a toy the combination with steering mechanism carried by said toy of means for controlling the position of said steering mechanism in accordance with guiding surfaces encountered by said controlling means and means for automatically and temporarily making said controlling means inoperative, such means comprising means for alternately raising and lowering the portion of the toy carrying said controlling means.

7. In a toy, the combination, with steering mechanism carried by said toy, of means

for controlling the position of said steering mechanism in accordance with guide-surfaces encountered by said controlling means, said controlling means consisting of a flanged fore-wheel of the traveling toy, an axle carrying said flanged fore-wheel and horizontal trunnions carrying said axle, and 2 a second wheel carried by the same axle, substantially as and for the purpose set forth.

In testimony whereof I have signed my name to this specification in the presence of 30 two subscribing witnesses.

WILHELM SADTLER.
